UNITED STATES PATENT OFFICE.

JOHN GROEME BALSILLIE, OF MELBOURNE, VICTORIA, AUSTRALIA.

WIRELESS-TELEGRAPH TRANSMITTER.

1,227,521.

Specification of Letters Patent.

Patented May 22, 1917.

Application filed September 12, 1913. Serial No. 789,568.

To all whom it may concern:

Be it known that I, JOHN GROEME BALSILLIE, a subject of the King of Great Britain and Ireland, residing at 51 Spring street, 60
5 Melbourne, in the State of Victoria, Australia, have invented certain new and useful Improvements in Wireless-Telegraph Transmitters, of which the following is a specification.

10 This invention relates to a wireless telegraph transmitter of the type in which the radiator is connected electrostatically to an exciting circuit as contra-distinctive from transmitters in which the radiator is connected inductively to the exciting circuit, and has for its object the provision of effective means for energizing the radiator by unidirectional impulses from an exciting circuit. The present invention consists in 15
20 means whereby the exciting circuit is caused to deliver trains of unidirectional impulses into the radiator intermittently without reaction; in an arrangement of the radiator and the exciting circuit whereby a high proportion of the energy stored in the exciting circuit may be emitted during periods of discharge through the radiator; and in means whereby pre-charging of the radiator is inhibited.

25 In the accompanying drawings Figures 1 and 2 are diagrammatic views of high efficiency transmitter circuits arranged according to this invention and including the said means for intermittently discharging the exciting circuit into the radiator, and for maintaining zero potential in the radiator. Fig. 3 is a sectional elevation of the discharge gap electrodes. Fig. 4 is a diagrammatic view of a T type air wire such as 30
35 is preferred for a radiator. Fig. 5 is a sectional elevation of an inductance contained in the exciting circuit in series with a plurality of condensers therein. Fig. 6 is a sectional elevation of an induction valve 40 with magnetic material core contained in the radiator in shunt with the connecting condenser.

45 The means for delivering energy into the exciting circuit from a primary source of energy do not form part of the present invention. They may consist of a generator directly connected in parallel with the condensers in the exciting circuit provided that the generator delivers electrical energy 50 of sufficient potential to pass across the discharge gap in the exciting circuit.

Those portions of the exciting circuit which are traversed by the feeding high tension energy function as a charging circuit.

65 In practice it is most convenient to use a primary power circuit interposed between the generator and the charging circuit, and to couple this primary power circuit to the charging circuit inductively through a transformer. This arrangement presents no novelty. The generator used in practice when an inductively coupled power circuit is used is preferably of the rotary converter type capable of supplying alternating current 70
75 energy having a periodicity of the order of 500 per second. The form of radiator is immaterial, though it is preferred to use a capacity type of antenna.

80 The circuit interposed between the radiator and the source of primary power functions as a charging and as an exciting circuit, certain of its elements only being operative during the charging period. This intermediate circuit is connected to the 85 radiator by means of a condenser common to both. When the intermediate circuit functions as a charging circuit and an inductively coupled power circuit is used its operative elements are the transformer secondary E, the condensers F and G, the line connections between those parts, and the inductance valve R. When it functions as an exciting circuit its operative elements are the condensers F, G and H, the rectifying discharge gap J, the line connections, and the reactance K.

90
95 The reactance K may include in its structure a sliding core or an equivalent part of iron or other magnetic material, or, if coreless, may be made variable by other means. When the potential across the condensers F and G Fig. 1, H and G Fig. 2, attains a value which exceeds the potential corresponding with the resistance of the discharge gap J the condensers discharge, the current passing over the gap J. This condenser discharge is very rapid, and tends to oscillate in the exciting circuit. The gap J is adjusted so that at the instant of maximum potential across the condensers, the latter discharge across the gap at a rate which is determined by the dimensions of the inductance K and the condensers F, H, and G. The rate at which the discharge occurs is adjusted so that energy is delivered 100
105 to the radiator at the rate at which the ra-

110

diator can best absorb it. The dimensions of the inductance R are such that it prohibits the flow of the discharge current through it.

If the inductance valve R be adjusted to zero value the charge in the condenser H is released by the discharge across the gap J and in consequence the radiator P becomes energized. When, however, the inductance valve R is adjusted to a higher value, the condenser H is charged by the discharge of the condensers G and H across the gap J, and in consequence, the radiator P becomes energized. The dimensions of the circuit including the transformer secondary E, the inductance K, condensers F, H and G, and the inductance R are such that that portion of the energy stored in the condensers and not absorbed by the radiator but reserved in charge by the single discharge of the condensers is returned to the primary source of power via the transformer E C, that is to say, that the rate of flow of current in this circuit must agree with the rate of flow of current in the primary circuit A B C D; briefly the circuit E K F R G is in resonance with the current in the circuit A B C D.

Fig. 3 illustrates a form of spark gap of the air cooled type which is effective for the purposes of this invention. The electrodes L and M of the discharge gap J are arranged in series with the condensers F, G, and H. The electrode L is a blunt nosed cone of metal of high electrical conductivity pierced axially with a hole about one sixtieth inch diameter and connected by a tube N of an insulating material with a pump or pressure reservoir O from which air or gas under high pressure is supplied and blown through said axial hole. The electrode M is a surface of metal of high conductivity mounted in front of the nozzle L and separated therefrom by a distance of about five sixteenths of an inch more or less. One such discharge gap is sufficient for a transmitter supplied with primary energy of 5 kilowatts. In practice the pump or reservoir O delivers air under a pressure of 100 to 105 pounds per square inch at the nozzles, but pressures up to 500 pounds per square inch may be employed. Only certain approximate pressures within the range required are usable, intermediate pressures producing undesirable effects. The volume of air or gas employed is that necessary to maintain the electrodes at a constant low temperature, while the velocity which is governed by pressure must be sufficient to remove the ionized air particles upon formation. The sparking distance, volume, and velocity of air must be adjusted until such a combination is reached that only one half of each complete cycle is permitted to discharge across the gap.

In one practical embodiment of my invention, the reactance K contains about 24 turns of copper tubing forming a coil of about twelve inches diameter, and, when of the core type, is arranged so as to be slide- 70 able longitudinally over a squirrel cage core composed of about 180 pieces of soft iron wire 22 B. W. G. about 21 $\frac{1}{2}$ inches long, the ends of said wires being mounted in end disks and when necessary supported on intermediate spacers.

The inductance valve R is a variable inductance constructed of two pancake spirals S and S¹ arranged foldably bookwise at either side of a slidably withdrawable plate 80 of magnetic material which constitutes a magnetic core. This core comprises a pack of about ten sheets each of 7 millimeter thickness of silicon steel insulated from each other by paper sheets; its area is approximately the area circumscribed by the coils. Each pancake is a heavily insulated spiral coil of 16 B. W. G. wire having about 16 turns, and an external diameter of about 15 inches preferably wound in the same direction. The mechanical form of this inductance valve is not essential to its successful operation, but it is practically necessary that it shall have a core of iron or light magnetic material, and that its inductance value shall be adjustable by alteration of the relative positions of the core and coils. This valve is adjusted to pass the charging current through it without substantial impedance; it is shunted around the 100 common condenser and therefore acts to discharge the potential at either side of that condenser without affecting the charge in the other condensers in the exciting circuit, and therefore insures a condition of zero 105 potential at the terminals of the radiator while permitting the exciting circuit to become charged. By reason of hysteresis effects, however, this valve operates during the period of discharge to choke back the 110 high frequency energy currents from the condensers with the result that the current is thrown through the common condenser and the radiator by which it is emitted as an oscillation and is prevented from oscillating 115 in the shunt and so discharging the radiator. This inductance valve therefore functions as a device which inhibits precharging of the radiator but insures the isolation of the upper and lower sections of the radiator at the 120 moment of discharge.

As a practical instance of a transmitter constructed according to my invention designed to radiate about 1 $\frac{1}{2}$ kilowatts in the radiating circuit when a primary energy of 125 about 3 kilowatts is employed an aerial constructed substantially as in Fig. 4 may be used wherein the arms are each about 145 feet long and the stem about 205 feet. The capacity of this air wire system is approxi- 130

imately .0024 microfarads and its natural period of oscillation 500,000 per second. The capacity of the connecting condenser H which is common to both the radiator and exciting circuits is .032 microfarads. The capacity of the fixed condenser F is .014 microfarads, and the capacity of the condenser G is the same. In adjusting the circuits the necessary value of the connecting condenser H is first determined; then the capacities of the fixed condensers F and G are adjusted till the charging circuit is in resonance with the primary circuit. The inductance K is then varied till the time value of the discharge determined by the constants of the exciting circuit is about 10% less than the time value of the oscillation of the radiator, which latter is determined by the radiator constant solely. It is essential that the condenser capacity be of the subdivided type more than two condensers being always employed in either arrangement shown in Figs. 1 or 2 respectively. The structure and proportion of the parts in the reactance and inductance valve are the same as hereinbefore particularized.

In operation in the case of either arrangement of condensers in Figs. 1 and 2 the alternator A supplies current to the primary circuit; this circuit is closed intermittently when transmitting signals by the manual movements of the sending key B. The primary voltage is stepped up in the transformer C—E. The induced current in the secondary E of this transformer energizing the charging circuits which includes the condensers F, G and H, the aerial being connected to earth through the inductance valve R it is not precharged, as during the charging process said valve offers a path for current through which the difference of potential between the upper and lower parts becomes equalized. When the condenser potential reaches a value determined by the length of discharge gap J the energy stored in the condenser system discharges across the gap and energy is delivered into the radiator through the connecting condenser. By having the frequency in the exciting circuit adjusted in conformity to the current pulsations in the generator circuit, an increase in efficiency is secured and the available energy is thrown into the radiator circuit at the instant when most useful.

What I claim as my invention and desire to secure by Letters Patent is:—

1. A wireless telegraph transmitter comprising an exciting circuit and a radiator connected thereto electrostatically and means for maintaining zero potential in the radiator during charging period.

2. In a wireless telegraph transmitter an exciting circuit and a radiator connected thereto electrostatically and a means for maintaining zero potential in the radiator

during charging period, and for producing a single impulse in the exciting circuit during the discharge period at and by each discharge.

3. In a wireless telegraph transmitter, a primary circuit containing a fixed frequency generator, an exciting circuit connected to said primary circuit and containing a plurality of condensers, and a radiator connected electrostatically to said exciting circuit through one of said condensers and containing means for maintaining zero potential in the radiator during the charging period, and means for tuning said exciting circuit to the period of said generator.

4. In a wireless telegraph transmitter an exciting circuit containing a plurality of condensers and a radiator connected thereto through one of said condensers, means for maintaining zero potential in the radiator during the charging period, and means for discharging the exciting circuit instantaneously through the radiator.

5. In a wireless telegraph transmitter an exciting circuit and a radiator connected thereto electrostatically, means for charging the exciting circuit at fixed regular periods, means for producing a single discharge in said exciting circuit for each charging period, the electrical constants of said exciting circuit being so adjusted as to render its natural period equal to that of the charging means, and means for maintaining the radiator at zero potential during the charging period.

6. In a wireless telegraph transmitter, the combination with a power source, an exciting circuit, and a radiator, said power source having a fixed frequency, of means for tuning the period of said exciting circuit to the generator frequency, and means for preventing the return of energy from the radiator to the exciting circuit.

7. In a wireless telegraph transmitter an exciting circuit containing a plurality of condensers in series and a radiator connected thereto electrostatically through one of said condensers, the capacity of which condenser is greater than the capacity of the other condensers, means for charging said exciting circuit, and means for discharging same through the radiator, and for rendering it passive in relation to the radiator frequency during the periods of discharge.

8. In a wireless telegraph transmitter an exciting circuit containing a plurality of condensers in series and a radiator connected thereto electrostatically through one of the said condensers the capacity of which is greater than the capacity of the other condensers of the series, means for charging said exciting circuit, means for discharging said exciting circuit through the radiator intermittently, and for rendering it

passive in relation to the radiator frequency during the periods of discharge, and means for maintaining the radiator at zero potential during the charging periods.

- 5 9. A wireless telegraph transmitter comprising an exciting circuit containing a plurality of condensers, a radiator connected thereto electrostatically through one of said condensers, means for charging the exciting circuit at fixed regular periods, means for alternately establishing in said condensers a charged condition in sympathy with the frequency of the charging current and a passive condition in relation to the radiator frequency, the natural period of said exciting circuit being equal to the charging period, means operating during said passive condition for discharging the exciting circuit through the radiator, and means for 15 maintaining the radiator at zero potential during the charging period.

10 10. In a wireless telegraph transmitter the combination of an exciting circuit comprising three or more condensers, a magnetic 25 material core reactance, and a rectifying discharge gap in series, a radiator including one of such said condensers and a magnetic material core induction valve shunted around said common condenser.

15 11. In a wireless telegraph transmitter comprising an exciting circuit and a radiator, said exciting circuit having three condensers in series, a radiator connected to one of said condensers, a shunt around said 30 last condenser, and means operative simultaneously for producing intermittently interrupting reactances in said exciting circuit and in said shunt.

20 12. In a wireless telegraph transmitter, 40 an exciting circuit containing capacity and inductance, a radiating circuit electrostatically connected to said exciting circuit, a unidirectional, arcless spark-gap bridging

45 said exciting circuit, a charging circuit inductively coupled to said exciting circuit, and means for impressing harmonic electro-motive force upon said charging circuit at a frequency corresponding to the frequency in said exciting circuit when the spark gap is inactive.

50 13. In a wireless telegraph transmitter, an exciting circuit containing capacity and inductance, a transformer secondary comprising a part of said exciting circuit, an arcless, unidirectional spark gap bridging 55 said exciting circuit and arranged as a shunt past said transformer, a radiator electrostatically connected to said exciting circuit, a charging circuit connected to the primary of said transformer, and means for impressing upon said primary circuit an alternating electromotive force whose frequency is substantially equal to the frequency of said exciting circuit when the spark gap is inactive.

60 14. In a wireless telegraph transmitter, an exciting circuit containing capacity and inductance, a transformer secondary comprising a part of said exciting circuit, an arcless, unidirectional spark gap bridging 70 said exciting circuit and arranged as a shunt past said transformer, a radiator inductively connected to said exciting circuit, a charging circuit connected to the primary of said transformer, means for impressing upon 75 said primary circuit an alternating electromotive force, and means for tuning said exciting circuit to the alternations of said alternating electromotive force.

65 In testimony whereof I have affixed my 80 signature in presence of two witnesses.

JOHN GROEME BALSILLIE.
